UNITED STATES PATENT OFFICE

CROSBY FIELD, OF BROOKLYN, NEW YORK, ASSIGNOR TO BRILLO MANUFACTURING COMPANY, INC., A CORPORATION OF NEW YORK

HOLDER FOR METAL WOOL OR THE LIKE

Application filed April 10, 1928. Serial No. 268,891.

The present invention concerns a holder for pads or wads of metal wool or the like.

An important object of the invention is to provide a holder of this character having wad engaging means which are well protected at all times against damaging contact with the hands of the user or the surface of the article being worked upon by metal wool.

10 Preferably, such securing means is in the nature of one or more wad impaling devices associated with the holder in such a way that the holder must be manually flexed to permit the impaling means to function, a 15 novel feature being that when released, the holder is automatically self-restoring to its normal position where it effectively guards the points of the impaling means. Simple flexure of the holder exposes the impaling means for the reception of a pad, and mere release allows the holder to force the pad firmly onto the impaling means and to cover the penetrating ends of the latter.

The holder is of simple, rugged, durable construction and the hands of the user will not be injured either by the metal wool or the impaling means even though the assembled wad and holder are carelessly handled or energetically used.

20 The invention may be more fully understood from the following description in connection with the accompanying drawings, in which

25 Fig. 1 is a transverse sectional view through a holder embodying the present invention, showing a pad or wad of metal wool attached thereto, this view being taken on the line 1—1 of Fig. 2;

30 Fig. 2 is a longitudinal sectional view on the line 2—2 of Fig. 1, with the wad omitted;

35 Fig. 3 is a view similar to Fig. 1, omitting the wad and showing the holder flexed to expose the wad impaling means, preparatory to attaching the metal wool;

40 Fig. 4 is a view similar to Fig. 1, but omitting the wad and illustrating a modification, this view being taken on the line 4—4 of Fig. 5;

Fig. 5 is a longitudinal sectional view on the staggered line 5—5 of Fig. 4;

Fig. 6 is a view similar to Fig. 4, but showing the holder flexed to expose the impaling devices preparatory to receiving a 55 wad of the metal wool;

Fig. 7 is a transverse sectional view through another modified type of holder, this view being taken on the line 7—7 of Fig. 8; and

Fig. 8 is a bottom plan view of the holder shown in Fig. 7.

In Figs. 1 to 3 inclusive, I have shown a holder formed of a single block of distortable resilient material such for instance as 65 rubber. This block provides a plate or body portion 10 having a shallow recess or pocket 11 in its under face. The block also defines upon the top of the plate a longitudinally extending, upstanding handle member 12. 70

While, for convenience of description, I have referred to the holder block as having longitudinal and transverse axes, it is to be understood that the block may be of circular or square contour, in fact, of any shape to 75 conveniently receive a wad of metal wool such as 13. These mats, wads or "pads" are commonly sold in various shapes and sizes.

The pocket 11 extends longitudinally of the block immediately under the handle 12 and its end walls 11a preferably incline outwardly. One side wall 11b of the pocket is straight, i. e., at right angles to the bottom of the plate, while the opposite side wall 11c is concave.

One or more pins 14 are disposed in substantial parallelism with each other and with the bottom of the plate 10. These pins each have one end embedded in the plate 10 at one side of the pocket and one end projecting through the pocket wall 11b into the pocket, the pointed ends of the pins lying closely adjacent the pocket wall 11c, preferably within the concavity thereof. Thus the concave pocket wall serves as a guard for the 95 penetrating ends of the pins.

To apply a wad of wool to the holder, the latter is grasped with one hand and the flap formed by one side of the plate 10 laterally of the handle is simultaneously flexed 100

upwardly as shown in Fig. 3. The wad 13 is then held in the other hand and forced edgewise into the pocket 11, being impaled on the pins 14. As the flap is released it 5 springs back to the position of Fig. 1, further forcing the wad onto the impaling pins and bunching it in the pocket as the previously distended pocket walls resume their normal shape. When the flap has snapped 10 back to normal position, the concave pocket wall 11c prevents the wool from slipping off the ends of the pins, and at the same time effectively guards the pin ends from contact with the user's hands as well as from contact 15 with the surface to be worked upon. The slight lip 11d formed by the wall 11c and the bottom of the plate 10 digs into the mat and further secures it.

In Figs. 4 to 6 inclusive, I have illustrated 20 a modification in which the handle 12a of the plate 10a is slightly wider than the handle of Fig. 1. This handle is longitudinally bifurcated by a deep generally V-shaped groove or notch 15, dividing it into two 25 sections and permitting longitudinal flexure of the body along the base of the notch as a bending line.

Thus, instead of merely bending up a flap to expose the ends of the pins 14a, half of 30 the body, including one handle section may be flexed as seen in Fig. 6, the bifurcated handle structure offering facilitating such flexing.

Here both side walls of the pocket 11 may 35 be straight and the pointed ends of the pins 14a hooked or curved upwardly at 14b to further secure an impaled wad from slipping off the pins. Pins 14a constitute the right angularly turned extensions of wire 40 arms 16 extending deeply up into one section of the handle. Arms 16 are connected by an integral compoundly curved wire run 17 embedded in such handle section. The curve tends to positively anchor the wire against 45 displacement in the rubber in case the adhesive bond loosens.

The method of impaling a wad with this 50 form of the device is as above described except that half of the body is flexed to distend the pocket and expose the ends of the pins. The hooked ends of the pins cooperate with the adjacent pocket wall to retain the impaled and bunched wad in place when the body automatically returns to its normal 55 undistorted shape, and such pocket wall again serves as a guard for the pin ends to prevent damage to hands or work.

In Figs. 7 and 8 I have illustrated a further modification in which a more positive 60 guard or keeper means is associated with the free ends of the impaling pins.

Here the plate 10b is formed with a relatively massive longitudinally extending handle 12b and the straight walled pocket 21 65 in the bottom of the plate is of approxi-

mately square formation and of greater width than the handle.

A pair of straight parallel pins 14b include ends embedded in one side of the plate and extend through one pocket wall transversely across the pocket, their free ends terminating adjacent the opposite pocket wall. The embedded ends of the pins are integrally connected by a compoundly curved or irregularly undulating length of wire 18 embedded in the plate and affording a firm anchorage. 70 75

Embedded in the other side of the plate is a wire member 19 corresponding in shape to the wire 18 but carrying at its ends keepers 20 for the pointed ends of the pins 14b. Such keepers project through the pocket wall adjacent the free ends of the pins and may be of any desired character. The ends of the wire 19 may be bent to form the 80 85 keepers 20 or the wire ends may carry V-shaped guard devices as shown, in which the pin ends are received.

It is of course desirable that the keepers be of such a nature that they automatically 90 engage the ends of the pins as the body flap snaps back to normal position after a wad impaling operation.

With all forms of the invention the wad impaling operation is substantially the same 95 and when the body, having been distorted to expose the pin ends, returns to normal position, a portion of the wad is bunched, forced more securely on the pins and held against loss while the pin ends are effectively guarded from damaging contact with either the user's hands or the surface of the work. 100

I claim:

1. A holder for a metal wool scouring pad, said holder having a disc-like body portion of relatively stiff resilient material having in one face a long relatively narrow recess having opposite longitudinal walls, said recess being of such depth that the holder may be readily bent along the line of said recess to convex the recessed face and diverge the lateral walls of the recess, and one of said walls having a plurality of pad-impaling members embedded therein and extending transversely across said recess, each having a free impaling end terminating closely adjacent an opposite wall of said recess when the holder is in normal unbent shape but exposed outside the recess when said holder is convexed along the line of said recess. 105 110 115

2. A holder for a metal wool scouring pad, said holder having a disc-like body portion of relatively stiff resilient material having in one face a long relatively narrow recess of such depth that the holder may be readily bent lengthwise of said recess to convex the recessed face and diverge the lateral walls of the recess, and pad- 120 125 130

trating members attached to one of said walls all projecting in the same direction transversely of said recess and substantially bridging said recess, and having their free ends inwardly curved and located within said recess when the holder is in normal unflexed position.

3. A holder for a metal wool scouring pad, said holder having a disc-like body portion of relatively stiff resilient material having in one face a long relatively narrow recess of such depth that the holder may be readily bent lengthwise of said recess to convex the recessed face and diverge the lateral walls of the recess; an elongated, projecting hand-grip parallel with and overlying the recess, on the opposite face of the holder thereby stiffening the holder against flexing transversely of the recess; and a plurality of pad-impaling members anchored in one side of said recesses and extending transversely across said recess, each having a free impaling end terminating closely adjacent an opposite wall of said recess when the holder is in normal unbent shape but exposed outside the recess when said holder is convexed along the line of said recess.

4. A holder for a metal wool scouring pad, said holder having a disc-like body portion of relatively stiff resilient material having in one face a long relatively narrow recess of such depth that the holder may be readily bent lengthwise of said recess to convex the recessed face and diverge the lateral walls of the recess; one of said lateral walls having pad-penetrating members all projecting in the same direction transversely of said recess and substantially bridging said recess, and having their entire lengths disposed wholly within said recess when the holder is in normal unflexed position.

Signed at Brooklyn in the county of
46 Kings and State of New York this 7th day
of April, A. D. 1928.

CROSBY FIELD.
